(57) **CLAIM**

I claim the ornamental design for a flag display container, as shown and described.

DESCRIPTION

FIG. 1 is a perspective view of a flag display container in an open configuration.

FIG. 2 is a top plan view of the container of FIG. 1.

FIG. 3 is a top plan view of the container of FIG. 1, with hook and loop straps separated.

FIG. 4 is a bottom plan view of the container of FIG. 1.

FIG. 5 is a front elevation view of the container of FIG. 1.

FIG. 6 is a rear elevation view of the container of FIG. 1.

FIG. 7 is a left side elevation view of the container of FIG. 1; the right side elevation view is a mirror image of the left side elevation view.

FIG. 8 is a perspective view of the container of FIG. 1, in a closed configuration.

FIG. 9 is a top plan view of the container of FIG. 8.

FIG. 10 is a bottom plan view of the container of FIG. 8.

FIG. 11 is a front elevation view of the container of FIG. 8.

FIG. 12 is a rear elevation view of the container of FIG. 8; and,

FIG. 13 is a left side elevation view of the container of FIG. 8; the right side elevation view is a mirror image of the left side elevation view.

The broken lines shown in the drawings are included for the purpose of illustrating portions of the flag display container that do not form part of the claimed design.
